UNITED STATES PATENT OFFICE.

SAMUEL E. AUSTIN, OF GARDEN CITY, KANSAS.

ATTACHMENT FOR AUTOMOBILES.

1,240,006.

Specification of Letters Patent. Patented Sept. 11, 1917.

Application filed February 16, 1916. Serial No. 78,665.

To all whom it may concern:

Be it known that I, SAMUEL E. AUSTIN, residing at Garden City, in the county of Finney and State of Kansas, have invented 5 a new and Improved Attachment for Automobiles, of which the following is a specification.

This invention is an attachment for automobiles adapted for being quickly applied to 10 the vehicle to serve as a side curtain and as a sun or wind shield and is more especially designed for use in connection with vehicle canopy tops and so mounted on the vehicle body that it does not interfere with the raising or lowering of the top.

In the practical application of side curtains for automobiles heretofore much used and in which is included a flexible cord or cable and curtain sections pendently supported on the said cable, so far as I know, 20 the curtain suspension means is fixedly attached to the vehicle top and so mounted that when not to be used, the curtain sections are slid along on the suspension cable, 25 gathered and then made fast on the underside of the top by suitable fastening means.

It has been found that in curtains constructed as above generally outlined, the cable suspension interferes with, and renders 30 it difficult to lower the top, particularly when handled by one person.

Again in the use of side curtains in which is included, a series of curtain sections pendent from an overhead suspension, special 35 means for securing the lower curtain ends is usually required, which takes time in adjusting the said lower ends as conditions may make necessary.

My invention, in its generic nature, embodies an improved curtain attachment for 40 automobiles that can be almost instantly applied while the vehicle is at rest or in motion and as quickly removed from the vehicle body, and that can be readily and compactly rolled up for conveniently storing it under the seat.

Furthermore, my improved curtain attachment includes means for so supporting a single piece curtain that extends the full 45 length of the side of the vehicle body and cooperatively connects with supporting elements removably mounted on the body for holding the curtain along the side thereof in such manner that the occupant of the vehicle

may conveniently and quickly adjust it to 55 extend up from the side rails of the body to partly or wholly close the side space between the top and the said side rails.

Furthermore, my invention includes means whereby the entire length of the curtain can 60 be raised from the lower end up; parts thereof between the ends either raised from the bottom or lowered from the top, while the remaining portions thereof extend the full vertical distance between the top and 65 the body rail, and which also has provision for disconnecting the front and the rear end portions of the curtain and their attached supporting means and close them against their next adjacent curtain supports and 70 fixedly sustained in such latter position.

My curtain attachment in its details of structure, includes simple and inexpensive means for holding the extreme front ends of the curtains to the side arms of the machine 75 wind shield, tension means, that form part of the suspension cable to which the curtain is applied, for holding the cable taut and allow for necessary extension of the cable when the upper edge of the curtain of one 80 portion is pulled down at an angle to the remaining upper edge portion thereof; certain other details of construction and novel combination of parts being also embodied in my improved curtain attachment, all of 85 which will be hereinafter first described, specifically pointed out in the appended claims and illustrated in the accompanying drawings, in which:

Figure 1 is a side elevation of an automobile, with my curtain attachment applied, the curtain being shown at its vertically extended position to form a complete closure between the canopy or top and the body rail.

Fig. 2 is a side view of a portion of the 95 vehicle body and the top, with my curtain applied, the latter being shown at an intermediate position, closing over but one-half the space between the top and the body.

Fig. 3 is a view similar to Fig. 2, the curtain being at the position shown in Fig. 2 with that portion over the rear door shown as pushed up to provide space for readily passing through the doorway.

Fig. 4 is a view similar to Fig. 2, with the 105 front end of the curtain, together with its front support, closed up against the next adjacent supporting member or standard.

Fig. 5 is a view showing the rear end of the curtain with its support moved up against the next supporting member.

Fig. 6 is a side elevation of the several standards that form the curtain supporting means and the upper and lower expandible cables that are held in the upper and lower hemmed portions of the curtain.

Fig. 7 is a transverse vertical section of one of the standards.

Fig. 8 is an enlarged vertical section of the telescoped ends of the two members that form the standard, and illustrates the friction spring bearing for holding the upper telescopic member to its vertical adjustment relatively to the lower member.

Fig. 9 is a similar view of one of the friction sleeves that slidably engages the lower standard member, and to which the lower edge of the curtain connects.

Fig. 10 is a detail perspective view partly in section, that illustrates one of the bracket bearings that support the curtain standards.

Fig. 11 is a modified construction of such bracket bearing, the same including a latch bolt device for engaging the lower end of the standard to hold it against pulling out of the bearing.

Fig. 12 is a view that illustrates one of the side curtains rolled up for storing.

Fig. 13 is a detail of a part of my curtain device showing the manner of connection to the support.

Fig. 14 is an enlarged detail perspective showing the lower hem and the pocket for the support.

Fig. 15 is a detail section illustrating my means for the attachment of the bracket to the car body.

Fig. 16 is a side elevation of my improved curtain attachment applied to an automobile with the top down.

In the drawings I have shown, a conventional type of touring car to which one of my curtain attachments is applied for use as a side curtain, and adjusted for closing the entire side of the machine between the drop portion of the top 1 and the side rails 2 of the car body, and in the said showing, I have illustrated five standards removably supported at their lower ends in brackets 3, secured to the body side, substantially flush with the top rail and to the said standards is secured a curtain 4, formed of a single piece, but which may be in sections extending across predetermined portions of the open sides of the motor car, and each section constituting a complete curtain structure. I prefer, however, to make the curtain of a single member as shown, since when of a single piece extending the full length of the car, it serves either as a side curtain, as a sun shield or as a wind shield.

The bracket bearings 3 one of which is shown in detail in Fig. 10, each consist of a

body portion having a tapered aperture 30 that extends vertically through the body, to keep the bearing socket free from dirt, and three laterally projected tapered lugs 31 for fitting into apertures 32, provided in the side of the auto body, and held by screws 33, and the washers 33^a on the inside of the body, and at this point it should be mentioned making the holes in the body for the bracket lugs is the only change or alteration of the vehicle necessary for the practical application of my invention.

The standards before referred to are all constructed alike and each is comprised of a lower member 7, whose bottom end is tapered to fit the tapered aperture 30 in the bearing bracket 3 into which it is seated when the curtain is to be operatively applied.

While the tapered end of standard member 7 and the tapered aperture in the bracket 3 is sufficient, under ordinary circumstances, for holding the curtain secure on the machine body, a latch device 8^a such as is illustrated in Fig. 11 may be used for locking the standard member 7 securely in its bearing 3, and the standard 7 has an annular groove 71 to receive the latch 8 as shown.

70 designates the upper standard member and it telescopically engages the lower member 7 as is best shown in Fig. 7, which shows the member 70 as passing through a screw cap mounted on the upper end of the member 7 and through a series of bow springs 9-9, that frictionally engage the member 70 to hold such member to any of its vertical adjustments, such mounting of the upper standard sections providing a simple means for holding the standard member 70 to any of its vertically shifted positions from the mid line of the side space between the top and the side rail of the body, up to and between the pendent flaps of the top, and to prevent pulling the upper member out of the lower standard 7, the lower end of the said upper member 70 has an annular flange 75 at the lower end that engages a screw stop 10 in the upper end of the lower or tubular standard 7 as shown.

The curtain body is secured on each standard in any approved manner.

In the drawing, the curtain is shown as having vertical pockets 11 secured on the outerside of the main curtain body, that receive their respective standards and at the upper end, each upper standard member 70 has a cap piece 72 and eye portions 73, to which the upper or suspension cable or cords 74 connect, and the said cords 74 are held in the upper hemmed edge of the curtain, see Fig. 3 which also shows each cable member 74, connected with each pair of adjacent standards 70 and provided with an elastic (coil spring) portion 76.

8 indicates the lower cable sections, also

provided with elastic portions 80, and are joined with adjacent pairs of standard members 7—7. Cables 8 are held in the hemmed portions 85 on the lower edge of the 5 curtain.

On each standard member 7 is slidably mounted a cuff or sleeve 9^a, that includes a screw cap 90, which contains spring bearings 91 for frictionally engaging the standard 10 and 7, to hold the sleeves at any of the vertically adjusted positions on the standard 7.

Each sleeve 9 has eye portions 93 to which the opposite ends of the cable sections 8 connect as is clearly shown in the drawing. To 15 hold the front end of the curtain taut, when it is applied for use, suitable means are attached to such end, for engaging the side bars of the front wind shield.

From the foregoing description taken in 20 connection with the drawings, the complete construction, the manner of its use and the advantages of my improved attachment will be readily apparent.

By reason of the simple co-operative connection of the several parts, the same can be 25 almost instantly applied for use, since all that is necessary is to slip the several standards into the brackets on the side of the car, and by pulling the upper standard sections 30 up to their limit, the curtain will open out and become a full side curtain, and when desired to close only one-half the space between the top and the side rail of the body, the occupant of the car simply need but 35 push the upper standard members 70 down into the lower members 7.

Since the upper cables and the lower cables are held taut between their points of connection with the standards, it follows 40 that the curtain may be readily pushed up from the bottom edge at any point between the standards or pressed down to the several positions indicated in the drawings, and automatically held at their different points 45 of adjustment by reason of the frictional engagement of the upper standards 70 with the lower standards 7 and the like engagement of the sleeves 9 on the standards 7.

What I claim is:—

50 1. The combination with the vehicle body and a top carried by said body and a plurality of spaced brackets along the top rail of the body; of a curtain attachment comprising a plurality of standards adapted to be 55 removably mounted on and projected vertically one from each of the said brackets, a flexible curtain that extends across all of the standards, each standard being vertically extensible, and means for flexibly connecting the upper edge of the curtain to the upper end of each of the standards, other

means for connecting the lower edge of the curtain with each of the standards, said upper and lower curtain connecting means consisting of elastic cable sections, one section 65 for each pair of adjacent standards.

2. In an attachment of the character described; the combination with an automobile body and a plurality of spaced brackets along the side of the body, a plurality of 70 standards, one for each bracket, said standards being adapted to be removably mounted on their respective brackets and each including a lower stationary member and an upper member that telescopically engages with the 75 lower member, a flexible curtain that extends the full length across all of the standards, means for flexibly connecting the upper edges of the curtain to the upper standard members, other means for flexibly 80 connecting the lower edge of the curtain onto the lower standard members, the means for flexibly connecting the lower edge of the curtain to the lower standards including elastic cables hemmed in the lower edge of 85 the curtain, and means for connecting their ends to adjacent ones of the lower standard members, said last named means including sleeves frictionally engaging the said standards. 90

3. In an attachment of the character described; the combination with an automobile body and a plurality of spaced brackets along the side of the body, a plurality of standards, one for each bracket, said 95 standards being adapted to be removably mounted on their respective brackets and each including a lower stationary member and an upper member that telescopically engages with the lower member, a flexible curtain that extends the full length across all 100 of the standards, means for flexibly connecting the upper edge of the curtain to the upper standard members, other means for flexibly connecting the lower edges of 105 the curtain onto the lower standard members, the means for flexibly connecting the lower edge of the curtain to the lower standards including elastic cables hemmed in the lower edge of the curtain, means for 110 connecting their ends to adjacent ones of the lower standard members, said last named means including sleeves frictionally engaging the said standards, said means for flexibly connecting the upper end of the 115 curtain to the upper standard members including elastic cables hemmed in the said upper edge of the curtain and connected at their ends to adjacent ones of the upper standard members.

SAMUEL E. AUSTIN.
